FIREPROOF METAL DOOR

Filed Sept. 7, 1926

Patented Aug. 7, 1928.

1,680,221

UNITED STATES PATENT OFFICE.

JOSIAH E. LEE, OF ERLANGER, KENTUCKY, ASSIGNOR TO THE ARCHITECTURAL METAL PRODUCTS, INCORPORATED, OF COVINGTON, KENTUCKY, A CORPORATION OF KENTUCKY.

FIREPROOF METAL DOOR.

Application filed September 7, 1926. Serial No. 134,037.

This invention relates to fire-proof metal doors that have hollow sheet-metal casings or shells, made in open rectangular-frame form and adapted to accommodate fire-proof 5 panels or inserts which are clamped along their four edges between the channeled or grooved inner edges of the said casings, and rivets or bolts then used in said clamped frame-and-panel joint-parts of the door for 10 securely fastening or connecting them together in door-unit form.

The object of the present invention is to provide new and improved means whereby man-holes are located along the surrounding 15 joint made by the clamped edges of the door-panel with the door outer-casing and coincident with each of the inner rivet or bolt fastenings, each man-hole being closed, sealed, or duly covered-over by means of a plane or 20 unelevated bridging film or other suitable filler, so that all of the said inner fastenings are effectually concealed, and each one of such closing films or membranes then adapted to be surfaced and finished to correspond 25 with the remaining outer surface of the said outer-casing, and thus absolutely eliminating all surface nails, screws, bolts and the like from the outer plane of the door-structure and leaving the inner moulding of the 30 casing entirely free from any defacing methods or effects, and yet, on the other hand, firmly and permanently held together in a single door-unit form that is at once durable and inexpensive and is otherwise 35 adapted to contain or house the customary inflammable wooden or like casing core or filler and any incidentally-added fire-proof plastic or like insulating-packing that may be placed within the cavities in the panel- 40 clamp moulding-edges of the casing, to subdue or prevent fire-communication to the said wooden core of the casing.

In the accompanying sheet of drawings, 45 Figure 1 is a fragmentary elevation showing the lower right-hand corner of a fire-proof metal door embodying my invention; Fig. 2, a horizontal section, on line α , α , Fig. 1, but with the man-holes for access to the inner rivet or bolt fastenings in normally-open 50 condition, and with the parts of the door all assembled and ready for the final closing or sealing of the man-holes to conceal them and the contents within the panel-clamp portion of the door-casing; and Fig. 3, a view like 55 unto Fig. 2, but with the said man-holes

closed and the door otherwise ready for final-finishing and use.

The hollow sheet-metal casing herein is made up of upright side-stiles 4, and cross-rails 5, a pair of each as customary in an open rectangular door-frame form, but I have shown a right-hand side-stile and a lower cross-rail to form the said lower right-hand corner of the door, that is just like the other three corners of the entire structure. 60 The inner edges of each of the side-stiles and cross-rails are formed or shaped into integral inwardly-extending mouldings 6 and 7, respectively, that each have a pair of spaced, corresponding, outwardly-extending, 65 parallel, right-angled flange-formations 8 that are adapted to form clamping-jaws for the skirt or outer edges of the customary panel 9 of the door, as best seen in both Figs. 2 and 3. The panel 9 is formed of a thick 70 slab or sheet of asbestos mill-board or like fire-proof material 10 incased between outer sheet-metal plates 11. A wooden or like core 12 is inclosed by the hollow stiles and cross-rails, and a central longitudinal groove or 75 recess 13 is provided in the inner edge of the core for the reception of the laterally-extended edges 14 of the said plated-panel 9 that become firmly seated or embedded therein when the stiles, cross-rails and panel are 80 assembled together and thus make up a decided single unit, as it were, of the entire fire-proof metal door structure herein.

In order to firmly and securely fasten the 85 edges of the said plated-panel in place between the clamping-jaws 8, 8, of the inner-edge mouldings 6 and 7 of the door-casing I provide bolts 15 that pass through aligned 90 holes made in the said clamping-jaws and the skirt of the panel, but, in order, also, to insert 95 the said bolts into connecting-position, I further provide aligned orifices or man-holes 16 and 17 in the mouldings 6 and 7 that are sufficiently or amply large for the convenient 100 handling of the bolts, including their fastening-nuts, and the requisite implements or tools, into and from the interior of the cavities or chambers at both sides of the said skirt of the panel, lying ahead of the embedded edges 105 of the panel in the wooden core or filler of the several stiles and cross-rails of the door-casing. Thus, the beveled fore-end of a screw-driver is inserted or seated in the cross-slot of the bolt-head and the socket-end 110 of a holding or detaining wrench is seated

upon the nut at the other end of the bolt, in the respective aligned man-holes 16 and 17, at which time the screw-driver is turned so as to drive the screw-bolt into tightening-
5 engagement with the said nut and thereby drawing the clamping-jaws into closing-contact with the said skirt of the panel. Of course, if preferred, the said socket-wrench can be used as a driver for the nut on the
10 screw-bolt and the slotted head of the latter held from turning by the seated beveled fore-end of the screw-driver, in clamping the skirt of the panel in place in the inner-edge mouldings of the stiles and cross-rails of the
15 door-casing.

A plastic fire-proof filling material 18 and 19 is then placed, if desired and deemed best, in the cavities at both sides of the bolt-chamber wherever a bolt is located in the
20 panel-fastenings to prevent fire communication to the inner wood-cores and then a covering or sealing film or bridging-membrane of solder or the like practically sightless closure 20 is used to entirely plug-up or close
25 the man-holes or orifices 16 and 17 wherever they occur in the structure, the outer faces of such plugs or seals 20 being flush with that of the several stiles and the cross-rails and the surfacing employed thereon, as well
30 as the same smoothing-up of the entire surface then done so as to effectually conceal the plugs from view and imparting to the said entire surface one of perfect uniformity and not defaced in any perceptible manner by
35 protruding bolts or other panel connecting or fastening means.

The said fastening-means may, if desired, extend to the use of rivets, spot-welding and other well-known methods that can all be
40 equally well accomplished or performed through the said man-holes or orifices 16 and 17 in the inner-edge clamp-mouldings of the door-casing.

I claim:—

45 1. In a fire-proof metal door, the combination of a rectangular metallic shell having upright side-stiles and horizontal upper and lower connecting cross-rails, mouldings provided in spaced pairs along the inner edges
50 of the said shell, spaced pairs of parallel flange-formations along the inner edges of

said mouldings and having aligned pierced holes, cores or fillers in said shell, longitudinal grooves provided along the approximate center of the inner edges of said core members, aligned man-holes made in the said mouldings in alignment with said pierced holes in the said flange-formations, a fire-proof panel fitting within the sight of said shell and having holes in its skirt aligning 55 with said moulding man-holes and adapted to be set in clamping-engagement with said spaced pairs of flange-formations on the mouldings and provided with extended edges that seat in said longitudinal grooves along 60 the inner edges of said core-members, and screw-bolts or the like passed through the said aligned man-holes and pierced bolt-holes into clamp-fastening engagement with the said flange-formations, substantially as 65 shown and described.

2. In a fire-proof metal door, the combination of a rectangular metallic shell having upright side-stiles and horizontal connecting cross-rails, mouldings provided in spaced 70 pairs along the inner edges of said shell, spaced pairs of parallel flange-formations along the inner edges of said mouldings and having aligned pierced holes, cores or fillers in said shell, grooves provided along the inner edges of said cores, aligned man-holes made in said mouldings in alignment with said pierced holes in said flange-formations, a fire-proof panel fitting within the sight of said shell and having holes in its skirt aligning 75 with said man-holes in the mouldings and adapted to be set in clamping-engagement with said spaced pairs of flange-formations and provided with extended edges that seat in said grooves in the cores, screw-bolts 80 or the like passed through the said aligned holes into clamping-engagement with the said flange-formations, and sealing membranes of solder, cement or the like inserted in said moulding man-holes with a filler 85 backing and providing a finished surface flush and in harmony with that of the moulding, substantially as shown and described.

In testimony whereof I have hereunto 90 affixed my signature.

JOSIAH E. LEE.
